W. F. MCKAY

DEVICE FOR USE IN SHIFTING TRAMWAY POINTS

Filed Aug. 22, 1924.

UNITED STATES PATENT OFFICE.

WILLIAM FLEMING MCKAY, OF ABERDEEN, SCOTLAND.

DEVICE FOR USE IN SHIFTING TRAMWAY POINTS.

Application filed August 22, 1924. Serial No. 733,503.

To all whom it may concern:

Be it known that I, WILLIAM FLEMING MCKAY, a subject of the King of Great Britain and Northern Ireland, and residing at 5 106 George Street, Aberdeen, Scotland, have invented a certain new and useful Improvement in Devices for Use in Shifting Tramway Points, of which the following is a specification.

10 This invention relates to devices for operating tramway points of the type including operating means on the car and operated means on the track, the operating means being duplicated and provided at each end 15 of the car.

A device according to the invention comprises a point box associated with a point and fitted with a lever fulcrumed between its ends and operatively connected to the 20 point. The lever is formed at one end as a lever-cam for engagement by the tramway wheel flange and is formed at the other end as a tappet for engagement by a cam formed on a tumbler pivotally mounted on 25 the point box and arranged in the path of a striker so fitted on the tramway car as to be under the control of the driver. When the lever-cam is engaged by the tramway wheel flange, the lever is rocked on its fulcrum and the point is moved to one side, and when the tumbler is engaged by the striker, the lever is again rocked whereby the point 30 is moved to the other side.

In the drawing Fig. 1 is a plan of the device; Fig. 2 is a section on the line 2—2 of Fig. 1 showing the striker in inoperative position; Fig. 3 is a detail view of the striker and tumbler mechanism showing the striker about to engage the tumbler; Fig. 40 4 a detail view of the striker and tumbler mechanism showing the striker restored by the tumbler to inoperative position; Figs. 5, 6 and 7 are respectively sections on the lines 5—5, 6—6, and 7—7 of Fig. 1; Fig. 8 45 is a perspective view of the tumbler.

The device shown comprises a point box 1 associated with which is a point 2 and in which is fitted a lever 3. The lever 3 is fulcrumed at 4 between its ends and is operatively connected to the point by a fork 5 50 engaging the point 2. One end of the lever is fitted with a plate 6 formed as a cam for engagement by the tramway wheel flange 7 and the other end of the lever is formed 55 at 8 as a tappet for engagement by a cam 9 formed on a tumbler 10 which is pivotally

mounted in the tramway rail at 11 and located in the box 1 in the path of a striker 13 so fitted on the tramway car 12 as to be under the control of the driver. When the lever-cam 6 is engaged by the flange 7 the lever 3 is rocked on its fulcrum 4 and the point 2 is moved to one side. When the tumbler 10 is engaged by the striker the lever 3 is again rocked whereby the point 2 60 65 is moved to the other side.

The striker and tumbler mechanism is constituted by a hook-like striker 13, pivotally mounted at 13' on the tramway car frame and normally sustained in elevated 70 position by a loaded latch 14 engaging a lug 14' on the striker 13, the latch being connected by a rod 15 to a bell-crank lever 15' which is connected to a pedal 16 under the control of the driver. The latch when 75 withdrawn permits the striker to occupy the operative position in which the tumbler is engaged. The tumbler is provided with an arm 17 formed with a notch 18 for engagement with the striker 13 and is associated with a weight 19 for restoring the tumbler to inoperative position. When the striker 13 is unlatched, the point thereof engages the notch 18 and, in the angular movement of the tumbler about its pivot from the 80 Fig. 3 position to the Fig. 4 position, the striker is displaced vertically into the elevated or inoperative position in which it is re-engaged by the latch.

To prevent damage to the mechanism due 90 to the lodgment of stones between the point 2 and the tramway rails the fork 5 is yieldingly connected to the point. The tines of the fork are located one on each side of the point and between each tine and the point is 95 interposed a spring 20, the arrangement being such that the fork may move in opposition to the springs 20 through its entire range notwithstanding that the point may be jammed.

100 What I claim is:—

1. For cooperation with a tramway car having flanged wheels, a downwardly extending striker mounted on said car, and means under control of the car driver for 105 rendering said striker operative, in combination, a tramway rail, a tramway point box adjacent to said rail, a tramway point, a point-operating lever operatively connected to said point and fulcrumed between its ends 110 in said box, the end remote from said point formed as a lever-cam engageable by a

wheel flange and the end adjacent to said point formed as a tappet, and a tumbler pivotally mounted on said rail and located in said box in the path followed by said 5 striker when operative so that the tumbler is engaged by said striker and caused to perform a partial rotation about its pivot, said tumbler having a cam-surface engageable with said tappet, the arrangement being 10 such that, when the lever-cam is engaged by the wheel flange, the lever and therewith the point are rocked into one position, and, when the striker engages the tumbler, the lever and therewith the point are rocked, 15 into another position.

2. For cooperation with a tramway car having flanged wheels, a downwardly extending striker mounted on said car, and means under control of the car driver for 20 rendering said striker operative, in combination, a tramway rail, a tramway point box adjacent to said rail, a tramway point, a point-operating lever yieldingly connected to said point and fulcrumed between its ends 25 in said box, the end remote from said point formed as a lever-cam engageable by a wheel flange and the end adjacent to said point formed as a tappet, and a tumbler pivotally mounted on said rail and located in said 30 box in the path followed by said striker when operative so that the tumbler is engaged by said striker and caused to perform a partial rotation about its pivot, said tumbler having a cam-surface engageable 35 with said tappet, the arrangement being such that, when the lever-cam is engaged by the wheel flange, the lever and therewith the point are rocked into one position, and, when the striker engages the tumbler, the

lever and therewith the point are rocked, 40 into another position.

3. For cooperation with a tramway car having flanged wheels, a downwardly extending hook-shaped striker mounted on said car, and means under control of the car driver for 45 rendering said striker operative, in combination, a tramway rail, a tramway point box adjacent to said rail, a tramway point, a point-operating lever operatively connected to said point and fulcrumed between its ends in said box, the end remote 50 from said point formed as a lever-cam engageable by a wheel flange and the end adjacent to said point formed as a tappet, and a notched tumbler pivotally mounted on 55 said rail and located in said box in the path followed by said striker when operative so that the tumbler is engaged by said striker and caused to perform a partial rotation about its pivot and concomitantly to 60 restore said striker to inoperative position, said tumbler having a cam-surface engageable with said tappet and being loaded so as to return to initial position after each actuation, the arrangement being such that, when the lever-cam is engaged by the wheel flange, the lever and therewith the point are 65 rocked into one position, and, when the striker engages the tumbler, the lever and therewith the point are rocked, into another 70 position.

In testimony whereof I have signed my name to this specification in the presence of two subscribing witnesses.

WILLIAM FLEMING MCKAY.
